RAILWAY CAR TRUCK

Edward P. O'Connor, Pittsburg, Kans.

Application November 27, 1935, Serial No. 51,836

7 Claims.

(Cl. 267—9)

My invention relates to railway car trucks and more particularly to a truck provided with a novel means of resiliently supporting the load to be carried thereby.

In the railway car trucks of the known art the bolsters are mounted upon a nest of springs, usually a group of four at each spring plank, or alternatively upon elliptical springs. These springs are compressed under load and shock and recoil with approximately a force equal and opposite to that which caused them to be compressed. This recoil results in periodic oscillations and vibrations which depend upon the speed, the load, the wheel and track conditions. These oscillations will pass through many cycles before the car returns to its normal riding plane. Excessive shocks due to spring recoil are transmitted to the car body and have been known to cause damage to the load, to the cars and to the track. Then, too, the oscillations resulting from excessive spring recoil cause rocking and bouncing which tend to permit the wheels to leave the rails, thus presenting a danger of derailment. The difficulties above mentioned are not eliminated by increasing the spring capacity. Numerous attempts have been made to counteract this known condition by the use of snubbers, shock absorbers and damping springs which are intended to break up the undesirable harmonic motions.

One object of my invention is to provide a spring construction in which periodic oscillations and vibrations are damped.

Another object of my invention is to provide a spring assembly which will give easy riding without the use of an excessive spring capacity.

Further and other objects of my invention will appear from the following description.

In the accompanying drawing which forms a part of the instant specification, which is to be read in conjunction therewith and in which like parts are indicated by like reference numerals in the various views.

Figure 1 is a side elevation of a railway car truck equipped with one embodiment of my invention.

Figure 2 is an end view of the railway car truck shown in Figure 1 with parts in section.

Figure 3 is a sectional view taken on the line 3—3 of Figure 4.

Figure 4 is a sectional elevation, on an enlarged scale, of a spring assembly used in the embodiment shown in Figures 1 and 2.

In general, my invention contemplates the use of a pair of cams forced outwardly by springs whose axes are at right angles to the thrust whereby the friction to movement of the cam surfaces will act as a damping force.

More particularly, referring now to the drawing, the wheels 1 support the customary axles 2 upon which are mounted the customary spring

planks 3. Supported by the spring planks are the spring assemblies of my invention which support the usual truck bolster 4 which in turn supports the railway car body.

The spring assembly comprises a lower member 5 and a like upper member 6. The member 5 is provided with a pair of longitudinally extending, inclined surfaces 7 and 8, and the upper member 6 is provided with a pair of longitudinally extending, inclined surfaces 9 and 10, as may be readily seen by reference to Figure 4. A cam member 11 is provided with cam surfaces 12 and 13 adapted to co-act with surfaces 9 and 7, and is positioned extending longitudinally between members 5 and 6, as can readily be seen by reference to Figure 4. A similar cam member 14 is provided with cam surfaces 15 and 16 adapted to co-act with surfaces 8 and 10, respectively, and is positioned similar to cam member 11. The cam members 11 and 14 are urged outwardly by a pair of springs 18. The springs are positioned about a pair of bolts 19 which pass through the cams 11 and 13. The bolts 19 are provided with heads 20 at one end and nuts 21 at their other ends. The bolt heads and nuts act as stops to limit the outward movement of the cam members 11 and 14. Also housed about bolts 19 are springs 22. These springs are shorter than are springs 18 so that they come into play only after cam members 14 and 11 have been urged inwardly.

In operation, the assembly is such that the lower members 5 are supported by the spring planks 3, as can readily be seen by reference to Figures 1 and 2. A channel member 24 provided

with upstanding flanges 25 and 26 is carried by the spring planks 3. The upstanding flanges prevent movement of the members 5. It is to be understood, of course, that any suitable securing

means may be employed for securing the lower members 5 to the spring planks. The upper members 6 directly support the truck bolster 4 as can readily be seen by reference to Figures 1 and 2.

Since the load is carried by the bolsters, any thrusts occasioned by the load will be directly transmitted to the upper members 6. It will be observed that the action will be to compress members 5 and 6, that is, to exert a force tending to move member 6 toward member 5. When this occurs, the inclined surfaces 9 and 10 of member 6 and the inclined surfaces 7 and 8 of member 5 will tend to force cams 11 and 14 inwardly toward each other, thus compressing springs 18.

It will be observed that there will be a movement of surface 9 with respect to surface 12, a movement of surface 9 with respect to surface 13, a movement of surface 13 with respect to surface 7, and a movement of surface 16 with respect to surface 8. The friction occasioned by this

movement will act as a snubbing or damping force.

Figure 5 is a side elevation of a truck having a spring assembly according to my invention.

Figure 6 is a side elevation of a truck having a spring assembly according to my invention.

Figure 7 is a side elevation of a truck having a spring assembly according to my invention.

Figure 8 is a side elevation of a truck having a spring assembly according to my invention.

Figure 9 is a side elevation of a truck having a spring assembly according to my invention.

Figure 10 is a side elevation of a truck having a spring assembly according to my invention.

Figure 11 is a side elevation of a truck having a spring assembly according to my invention.

means, preventing harmonic motions. If the shock is great or the load is sufficiently great, the inward movement of cam members 11 and 14 will be such that springs 22 will come into play, providing for greater spring capacity. If the load is heavy, the movement will be sufficient so that the benefit of both springs 18 and 22 is obtained. A similar action takes place upon recoil, the force stored in the springs pushing cams 11 and 14 and camming members 5 and 6 apart.

It will be seen that I have accomplished the objects of my invention. In the conventional spring arrangement, aside from undesirable oscillations and harmonic motions, it is impracticable to change the spring capacity for different loadings. In my construction, the spring capacity is governed within limits by the requirements of the load. With the conventional spring arrangement there is considerable variation in the height of couplers above the rails as between light and loaded cars due to the fact that a variation of loads cause different compression of the springs. With the railway truck of my invention the vertical variation is reduced by one half due to the fact that one half of the movement is converted to a direction along a horizontal axis. It will be observed that this gives my spring arrangement another desirable characteristic along the standpoint of maintenance. The action of friction in the truck assembly of my invention acts as a snubber for applied shocks as well as the shocks of reaction, thus reducing side sway, harmonic and spring motion. A railway freight car equipped with the spring assembly of my invention proved to be a smooth, easy riding car. There is less tendency to bouncing, damage to freight is minimized and a less danger of derailment exists.

It will be understood that certain features and sub-combinations are of utility and may be employed without reference to other features and sub-combinations. This is contemplated by and is within the scope of my claims. It is further obvious that various changes may be made in details within the scope of my claims without departing from the spirit of my invention. It is, therefore, to be understood that my invention is not to be limited to the specific details shown and described.

50 I claim as my invention:

1. In a railway truck a spring assembly comprising in combination, a channel member having a pair of upstanding flanges formed with downwardly and inwardly inclined surfaces, a second channel member spaced above said first channel member having flanges formed with upwardly and inwardly inclined surfaces, a pair of cam members positioned between said channel members having inclined surfaces in contact with the inclined surfaces of said channel members, a coil spring horizontally positioned between said cam members urging them to cam said channel members apart, and a limiting rod axially positioned within the spring for limiting the outward movement of said cam members.

2. In a railway truck a spring assembly comprising in combination a channel member having a pair of upstanding flanges formed with downwardly and inwardly inclined surfaces, a second channel member spaced above said first channel member having flanges formed with upwardly and inwardly inclined surfaces, a pair of cam members positioned between said channel members having inclined surfaces in contact with the

inclined surfaces of said channel members, a pair of horizontally positioned coil springs of different length lying transversely of the truck and positioned between said cam members, the construction being such that the longer of said springs urges said cam members apart under light loads and both of said springs urge said cam members apart under heavy loads, and means for limiting the outward movement of said cam members.

3. In a railway truck comprising in combination, wheels mounted upon axles, a pair of spring planks supported by said axles, a pair of channel members supported by said side frames, each of said channel members being provided with a pair of upstanding flanges formed with inclined surfaces, a second pair of channel members positioned above said first channel members and provided with downwardly extending flanges formed with inclined surfaces, a pair of cams having inclined surfaces in contact with the inclined surfaces of the channel members positioned between each pair of channel members, a plurality of horizontally disposed coil springs having their axes parallel to the axles of the truck and positioned between each pair of cam members normally urging the same outwardly to cam said channel members apart, and a bolster supported by said upper channel members.

4. In combination with railway trucks for rolling stock, spring assemblies comprising upper and lower cam surfaces, cam followers contacting the upper and lower cam surfaces, coil spring members positioned between the cam followers having their axes substantially parallel to the truck axles and serving as the sole support for the weight imposed on the spring assemblies.

5. In combination with railway trucks for rolling stock, spring assemblies comprising upper and lower cam surfaces, cam followers contacting the upper and lower cam surfaces, double coil springs of different lengths between the cam followers and arranged transversely of the trucks, adapted to support the entire weight imposed on the spring assemblies and dampen periodic vibration.

6. In combination with railway trucks for rolling stock, spring assemblies comprising upper and lower cam surfaces, cam followers contacting the upper and lower cam surfaces, means for limiting the outward movement of the cam followers, horizontally positioned coil springs of different lengths arranged transversely of the trucks and between the cam followers, adapted to support the entire weight on the spring assemblies and dampen periodic vibration.

7. In a railway truck a spring assembly comprising in combination a channel member having a pair of upstanding flanges formed with downwardly and inwardly inclined surfaces, a second channel member spaced above said first channel member having flanges formed with upwardly and inwardly inclined surfaces, a pair of cam members positioned between said channel members having inclined surfaces in contact with the inclined surfaces of said channel members, a pair of horizontally positioned coil springs lying transversely of the truck and positioned between said cam members, the construction being such that the coil springs serve as a sole support for the weight imposed upon the spring assembly, and limiting rods passing through each of said springs to limit the outward motion of said cam members by said springs.

EDWARD P. O'CONNOR.
